UNITED STATES PATENT OFFICE.

GEORGE MALPASS, JR., OF PHILADELPHIA, PENNSYLVANIA.

KNITTING-MACHINE NEEDLE.

SPECIFICATION forming part of Letters Patent No. 363,153, dated May 17, 1887.

Application filed January 5, 1887. Serial No. 223,436. (No model.)

To all whom it may concern:

Be it known that I, GEORGE MALPASS, Jr., a citizen of the United States, residing in Philadelphia, Pennsylvania, have invented certain 5 Improvements in Knitting-Machine Needles, of which the following is a specification.

My invention relates to that class of knitting-machine needles which have jacks of sheet metal the bits of which are thickened and 10 strengthened by re-enforcing plates, the object of my invention being to effect the attachment of these re-enforcing plates to the bits of the jacks more securely than by the usual plan of soldering.

15 In the accompanying drawings, Figure 1 is a perspective view, on an enlarged scale, of a knitting-machine-needle jack having its bit strengthened by a re-enforcing plate in the usual manner; Figs. 2, 3, and 4, perspective 20 views, also enlarged, of a jack having its bit re-enforced in accordance with my invention, Fig. 4 being partly in section; Fig. 5, a view, partly in section and partly in elevation, of the finished jack; and Figs. 6 to 9, sectional 25 views illustrating modifications of the invention.

In Fig. 1, A represents a jack for a knitting-machine needle, a being the stem of the jack, notched at the top for the reception of the 30 lower end of the needle-shank, and having in front a projecting bit, b, which is thickened and strengthened by means of a re-enforcing plate, d, folded around the bit. Usually this re-enforcing plate is retained by soldering it to 35 the bit; but this method is insecure, and hence objectionable.

In carrying out my invention, therefore, I form in the bit b of the jack a slot, f, and I notch the opposite sides of the re-enforcing 40 plate d so as to form tongues i i', the former being, by suitable machinery, bent laterally through the slot f of the bit, and then caused to overlap the tongues i', which are thereby deflected into the slot, as shown in Figs. 3, 4, 45 and 5, the length of the slot being sufficient to permit such deflection. The re-enforcing plate is thus rigidly and securely confined to the bit of the jack, irrespective of any solder, and the latter may be dispensed with, if desired, 50 although I prefer to apply solder after the re-

enforcing plate has been locked to the bit in the manner set forth, the solder being not so much for adding to the security of the fastening as for filling up the opening in the bit and the recesses caused by the bending of the 55 tongues. (See Fig. 5.)

If desired, but one side of the re-enforcing plate may be provided with tongues, as shown in Fig. 6, for instance, these tongues engaging directly with the bit a, and the bent end of 60 the tongue being contained in the slot of the bit, as shown at the lower portion of Fig. 6, or being contained in a slot in the opposite side plate of the re-enforce, as shown at the upper portion of said figure. 65

As shown in Figs. 2 to 6, the re-enforcing plate is in one piece, bent or folded around the bit of the jack; but separate plates may, it will be evident, be employed in place of the single plate, as shown in Fig. 7, for instance, 70 and there may be but one slot in the bit of the jack, as shown in Figs. 2 to 5, or upper and lower slots for the reception, respectively, of the upper and lower tongue or tongues of the re-enforcing plate. 75

When the bit has but a single slot, the re-enforcing plate may have but a single tongue, bent into the slot, as shown in Fig. 8, or through the slot and into a slot in the opposite side of the re-enforcing plate, as shown in Fig. 80 9, so as to form upper and lower retaining shoulders or stops, such as are formed by the tongues i in Fig. 6, and by the tongues i' in Figs. 2, 3, 4, 5, and 7.

I claim as my invention— 85

1. The combination of the jack having a slotted bit with a tongued re-enforce having its tongued portion bent into the slotted portion of the bit, all substantially as specified.

2. The combination of the jack having a slotted bit with a tongued re-enforce having upper and lower retaining shoulders or stops within the slot of the bit, all substantially as specified.

3. The combination of the jack having a slotted bit with a re-enforce the opposite side plates of which have engaging tongues bent into the slotted portion of the bit, all substantially as specified.

4. The combination of the jack having a

slotted bit, a tongued re-enforce having its tongued portion bent into the slotted portion of the jack, and solder filling the openings and spaces caused by the bending of the 5 tongued portion of the re-enforce, all substantially as specified.

In testimony whereof I have signed my name

to this specification in the presence of two subscribing witnesses.

GEORGE MALPASS, JR.
